UNITED STATES PATENT OFFICE.

JAFEW S. VAN BUREN, OF ALBANY, NEW YORK, ASSIGNOR TO ABRAM COX STOVE COMPANY, OF PHILADELPHIA, PENNSYLVANIA, A CORPORATION OF PENNSYLVANIA.

DESIGN FOR A COMBINED GAS AND COAL RANGE.

45,662.

Specification for Design.

Patented Apr. 21, 1914.

Application filed February 21, 1914. Serial No. 820,362. Term of patent 14 years.

To all whom it may concern:

Be it known that I, JAFEW S. VAN BUREN, a citizen of the United States, residing in Albany, county of Albany, State of New York, have invented a certain new, original, and ornamental Design for a Combined Gas and Coal Range, of which the following is a specification, reference being had to the accompanying drawing, forming part thereof,

the figure in which is a perspective view showing my new design.

I claim:—

The ornamental design for a combined gas and coal range substantially as shown.

JAFEW S. VAN BUREN.
